CONTAINER CAPPING AND TYING MACHINE

Gunnar Arnberg, Lidingo-Brevik, Sweden, assignor to Paterson Pacific Parchment Co., San Francisco, Calif., a corporation of California

Application March 6, 1936, Serial No. 67,503

10 Claims.

(CL 226—80)

This invention relates to improvements in container-capping and tying machines and is, in the present instance, illustrated in the form of a machine for applying and tying a skirted paper cap over the mouth of a bottle.

Bottles ordinarily closed by a disk of pasteboard pressed into a recess at the bottle mouth, as is common practice in the dairy industry, are unsanitary in that the top of the closed bottle presents a depressed area for the reception of germ-carrying substances and, further, in that the rim or pouring lip of the bottle, over which the contents must be poured, is exposed to contamination during handling and shipping.

Skirted paper caps of various types have been used to protect the tops of bottles, and various methods and materials have been employed to secure the caps to the bottles.

The principal object of the present invention is to provide an improved machine for forming and securing a cap over the mouth of a container. A further object of the invention is the provision in such a machine of improved means for forming a knot or tie of string or like material used for securing the cap to the bottle. A further object resides in the provision in such a machine of means for cutting paper blanks from a continuous strip and placing them over the container properly centered with respect to printed matter occurring at spaced intervals on the paper strip. Further objects of the invention will appear in the following specification, wherein detailed reference is made to the accompanying drawings, illustrating one form of the invention.

While the invention is described and illustrated in the form of a machine designed specifically for the purpose of capping milk bottles, it will appear and should be understood that many of the features disclosed are applicable to capping or tying other forms of containers or packages. The terms "bottle," "paper" and "string" are, therefore, to be understood as including any kind of container and any suitable form of covering and securing materials.

In the drawings—

Fig. 1 is a side elevation of a bottle capping and tying machine embodying my invention.

Fig. 1a is a detail view illustrating in reduced scale two of the cams which control the movements of some of the parts illustrated in Fig. 1.

Fig. 1b is a similar view of another of said cams.

Fig. 2 is an elevation of the opposite side of the same machine.

Fig. 3 is an enlarged vertical central section of

the upper portion of the machine illustrated in Figs. 1 and 2.

Fig. 4 is a fragmentary sectional view of a portion of the mechanism illustrated in Fig. 3.

Fig. 5 is a perspective view of one of the elements illustrated in Fig. 4.

Fig. 6 is a sectional view, taken on the line VI—VI of Fig. 1.

Fig. 7 is a sectional view, taken on the line VII—VII of Fig. 1 and illustrating the position of the parts with the bottle in raised position after the cap has been formed thereon and the tie placed around the same.

Fig. 8 is a plan view of a portion of the machine with a part of the top table and other structure broken away.

Fig. 9 is a sectional view, taken on the line IX—IX of Fig. 3.

Fig. 10 is a sectional view, taken on the line X—X of Fig. 3.

Fig. 11 is an enlarged sectional view, taken on the line XI—XI of Fig. 3 and illustrating in detail a portion of the tie-forming mechanism.

Fig. 12 is a sectional view of another portion of the same mechanism, taken on the line XII—XII of Fig. 3.

Fig. 13 is a view similar to Fig. 11, showing another position of the elements during the forming of a tie.

Fig. 14 is a view similar to Fig. 12, showing the position of the elements in a different stage of the tie-forming operation.

Fig. 15 is a view similar to Fig. 11, showing the position of the parts in another stage of the operation.

Fig. 16 is a perspective view of portions of the tie-forming mechanism, illustrating the manner in which the tie is supported prior to its being released for engagement with the bottle cap.

Fig. 17 is a sectional view, taken on the line XVII—XVII of Fig. 18, of a portion of the driving mechanism for the tie-forming grippers.

Fig. 18 is a sectional view of the same mechanism, taken on the line XVIII—XVIII of Fig. 17.

Fig. 19 is a sectional view of the same mechanism, taken on the line XIX—XIX of Fig. 17.

Fig. 20 is a perspective view, with certain elements illustrated as spread apart, of the mechanism illustrated in Figs. 17 to 19, inclusive, and with the cams which actuate said elements illustrated in a reduced scale.

Fig. 21 is a sectional view, taken on the line XXI—XXI of Fig. 3.

Fig. 22 is a sectional view, illustrating in detail

the construction of a part of the mechanism illustrated in Fig. 21.

Fig. 23 is a detail view of a cam which operates the paper feed drive illustrated in Fig. 24.

Fig. 24 is an enlarged view of a portion of the paper feed drive.

Fig. 25 is a sectional view, taken on the line XXV—XXV of Fig. 21 and showing the details of construction of a portion of the mechanism illustrated in Fig. 24.

Fig. 26 is a view, taken on the line XXVI—XXVI of Fig. 3.

The machine, as illustrated in the drawings, comprises a rectangular base 1, upon which are mounted a set of four corner posts 2, supporting at different elevations a lower table 3, an intermediate table 4 and an upper table 5. A pair of bearing brackets 6, mounted upon the base, support a main drive shaft 7, to one end of which is fixed a drive pulley 8 by which the drive shaft may be rotated through the means of a belt and a motor, or the equivalent. The drive shaft 7 carries a set of cams, generally indicated at 9 and arranged at intervals along the shaft between the bearing brackets 6. Two pairs of brackets 10 and 11, also mounted on the base 1, carry transversely extending shafts 12 and 13, respectively, which shafts support a plurality of levers and bell cranks, each of which will be hereinafter described in detail, for cooperation with the several cams included in the set 9 carried by the drive shaft.

In the form of the invention illustrated, the power for most of the major operations is obtained, and the operations are timed, through this system of cams and levers. It is to be understood, however, that the means disclosed is merely illustrative of a simple form of mechanism for obtaining the required mechanical movements, and that any one of many forms of driving and timing mechanisms may be employed for this purpose.

Referring to Figs. 1, 2 and 3, a bottle elevator is shown as operating through an opening in the lower table 3. This elevator is in the form of a plunger comprising a head 14, normally disposed in the plane of the table and of a size to receive a bottle 15. A skirt 16 depending from the head 14 cooperates with the opening in the table 3 to guide the upper end of the elevator as it is vertically reciprocated. A rod 17 supports the head 14 and is guided for vertical sliding movement by a bearing 18 adjacent to its lower end. The elevator is raised and lowered a desired distance and at properly timed intervals to bring the bottle 15 into position for the capping and tying operations to be performed upon it.

To raise and lower the elevator, a link 19, pivotally connected to the rod 17, is actuated by a bell crank 20 which rocks about a pin 21 carried by a bracket 22 on one of the corner posts 2. The upper end of the bell crank 20 is connected by an adjustable link 23 with the upper end of a bell crank 24, the lower end of this bell crank being provided with a roller 25 for engagement with a cam 26, which is one of the set of cams indicated at 9 (see Fig. 1a). A spring 27, extending between the bell crank 24 and one of the corner posts 2, maintains the roller 25 in contact with the cam 26; and the contour of the cam is such that the bottle elevator is caused, through the linkage just described, to raise the bottle into a position for the capping and tying operation and to lower the bottle after these operations have

been performed, once after each revolution of the main drive shaft 7.

Any desired form of mechanism may be employed for placing the bottles successively upon the elevator when it is at the level of the table 3 and for removing the bottles, one at a time, after the capping and tying operations have been performed. Such conveying mechanisms are found as standard equipment in connection with bottle and can handling machinery and form no part of the present invention.

A paper blank from which the bottle cap is to be formed is placed over the top of the bottle as it is being raised by the elevator. The paper for carrying these blanks is carried on a roll 30 (see Figs. 1 and 2) wound about a spindle 31, which is carried for free rotation in notches formed at the outer ends of a pair of spaced bracket plates 32 secured to two of the frame posts 2. As the leading edge of the paper leaves the roll 30, it passes under a rubber roller 33 (see Fig. 3) carried by brackets 34 adjustably supported upon a shaft 35, and the paper is thus urged into close contact with the face of a vacuum chamber 36 over which it passes for a purpose presently to appear. The paper then passes over a driven feed roller 37, against which it is held by a resilient roller 38 on pivoted arms 39 which are urged downwardly under the influence of a spring 40. The paper is advanced at timed intervals by the feed roller 37, and a knife 41 severs a measured length from the leading end. Prior to the severing action of the knife, the end of the paper is guided and supported between two sets of conveyor belts 42 and 43, by which it is maintained in a horizontal plane and guided to a position for reception between a pair of grippers 44 which grip and carry the severed piece of paper to a position directly over the top of the bottle on the elevator.

It is desirable that the paper carry a printed legend to advertise or classify the contents of the bottle, and the printing is preferably done on a regular printing press before the paper is placed on the roll. Such legends, appearing at 45 in Fig. 6, must be carefully centered with respect to the bottle top in order that they present a neat appearance and assume a position in which they may be read before the cap is removed from the bottle.

Assuming that a five inch square of paper is required for each cap, a roll of paper five inches wide is used, and the legends 45 are printed on the paper at five inch intervals. It is then necessary that the paper be cut at points equidistant from the centers of the printed legends as it is advanced to the cutting knife. Theoretically, the simple expedient of advancing the paper exactly five inches for each cutting operation would result in the proper centering of the legends printed thereon. It is apparent, however, that the slightest variation in measurement will, if continued as the paper is periodically advanced, result in marked misalignment. Even though the legends were to be spaced with the utmost precision and the driving mechanism perfectly controlled, the slight discrepancy caused by shrinkage or expansion of the paper would, upon continuous operation, result in serious error.

To insure proper centering of the legends upon the square blanks from which the bottle caps are to be formed, the feed of the paper is controlled by indicators formed on the paper itself. Indicators for this purpose may be, as shown at 46 in Fig. 6, in the form of small semi-circu-

lar cuts in the paper, equally spaced and half way between the centers of the printed legends 45. The manner in which such indicators control the paper feed and control centering of the printed legends will appear in the following description of the paper feed mechanism.

Referring particularly to Figs. 6 and 26, the feed roller 37 which advances the paper is illustrated as carried by a shaft 50, which is journaled in the bracket plates 32. A hub 51 is loosely mounted upon the shaft 50 and carries a gear 52 and a cam 53. The outer face of the cam 53 is ground flat and serves as a clutch surface co-operating with a similarly ground inner face of a ratchet wheel 54, which is splined to the shaft 50. A spring 55 is compressed by a nut 56, threaded upon the outer edge of the shaft 50 to urge the ratchet wheel inwardly and produce friction between the clutch faces, to the extent that rotation of the gear 52 will cause rotation of the ratchet wheel and shaft 50 to feed the paper, unless the ratchet wheel is restrained against movement. The gear 52 meshes with a gear 56 keyed to a countershaft 57, which also is journaled between the bracket plates 32 and which is provided adjacent to its opposite end with a gear 58.

A housing 59, which is also illustrated in Fig. 24, encloses the gear 58 and also serves as a guide for a rack bar 60 which meshes with the gear 58. The rack bar is, as illustrated in Figs. 2, 23 and 24, connected by an adjustable rod 61 with a bell crank 62 carried on the shaft 13 and provided with a roller 63, at its lower end, for engagement with a cam 64, which is another one of the set of cams, generally indicated at 9. A spring 65 urges the roller against the cam, and the contour of the cam is such that the rack bar 60 is caused to reciprocate once for each cycle of operation of the main shaft 7, thus causing the gear 58 to rotate alternately in opposite directions.

As illustrated in Fig. 22, the gear 58 is free to rotate relative to the shaft 57, but is formed with a flange 66 to which is pivoted a pawl 67 pressed by a spring 68 into engagement with a notched cam 69 (see also Fig. 25). The notched cam 69 is secured to the shaft 57 so that upon the upward stroke of the rack bar 60, the pawl rides over the outer surface of the cam without driving the shaft 57, but upon a downward stroke of the rack bar, which imparts rotation to the gear 58 and flange 66 in the opposite direction, the pawl 67 engages with a notch of the cam 69 and drives the shaft 57 to impart rotary movement to the feed roller 37 through the gears 56 and 52 and the friction clutch above described. The driving movement effected by reciprocation of the rack bar 60 is sufficient to advance the paper the required distance to form one blank, plus sufficient distance to more than compensate for any probable error, due to mechanical inaccuracies and error that may be caused by shrinkage or expansion of the paper.

In order to interrupt the driving movement of the paper at precisely the right time to insure proper centering of the printed legend thereon with respect to the blank that is to be cut, a pawl 70 (see Fig. 1) is pivoted on a shaft 71 so that it may swing into engagement with the toothed periphery of the ratchet wheel 54 to stop the rotation of the wheel, thus causing slippage of the clutch and rendering the paper drive means ineffective. The shaft 71, which carries the pawl 70, also carries a lever 72 (see Figs. 3 and 21). A spring 73, engaging with the lever 72, normally

urges the pawl 70 into contact with the ratchet wheel.

In order to hold the pawl out of contact with the ratchet wheel, a rod 74 connects the lever 72 with a flexible diaphragm 75, which forms the back wall of the vacuum chamber 36. The face of this chamber over which the paper passes is provided with a port 76 and a vacuum is maintained in the chamber through a connecting port 77 (see Fig. 6) which is in communication, by means of a hose 78 and suitable fittings, with a vacuum pump (not shown). So long as the paper covers the port 76 in the face of the vacuum chamber, the diaphragm 75 is drawn inwardly and through the rod 74 swings the lever 72 and shaft 71 to a position maintaining the pawl 70 out of contact with the ratchet wheel 54. As the paper is advanced, the vacuous condition is retained in the chamber 36 until one of the indicators 46, formed in the paper, registers with the port 76 in the face of the vacuum chamber. As the indicators are semi-circular cuts in the paper, they form valves or flaps, which will be drawn inwardly upon registry with the port 76 to break the vacuum and permit the spring 73 to urge the pawl into engagement with the ratchet, whereupon the feed of the paper will be instantly interrupted.

It should be understood, however, that the semi-circular shape of the indicators is not essential to their successful functioning but is chosen because of simplicity in the forming operation. Perforations of any shape will serve equally as well to admit air to the vacuum chamber. The indicators 46, whatever their shape may be, are formed half-way between the printed legends on the paper and are, therefore, intercepted by the lines at which the paper should be cut to effect proper centering of the legends. The port 76 in the vacuum chamber is spaced from the cutting knife a distance equal to the length of two blanks so that when one of the indicators registers with the port, another indicator will be positioned directly beneath the cutting knife and the paper will be severed at the proper point.

The paper feeding operation for the next succeeding operation of the machine must be preceded by the removal of the pawl 70 from its engagement with the ratchet wheel 54. To this end, the pawl carries a pin 80 (see Figs. 1 and 21) engaging the periphery of the cam 53, which is circular except for a relieved section at 81. The regular circular portion of the cam prevents engagement of the pawl 70 with the ratchet wheel 54, but the cam is so timed that the pin 80 registers with the relieved section 81 during the portion of the cycle when the pawl is to be applied to the ratchet by means of the vacuum control mechanism above described. At the end of a paper-cutting cycle, the pin 80 rests at the end of the relieved section 81 of the cam, so that upon the initial movement of the cam effected by the next succeeding cycle, the pin will ride out of the relieved section and the pawl will be released from the ratchet wheel 54 to permit feeding of the paper through the medium of the drive mechanism, which includes the friction clutch.

The conveyor tapes 42 and 43 (illustrated in Figs. 3 and 9) are driven intermittently and in timed relation with the paper feed mechanism. These tapes are carried by idler rollers 84 and drive rollers 85. The spindles of the drive rollers are fitted with intermeshing gears 86 (see Fig. 2), the lowermost of which also meshes with an idler gear 87 which is driven by a gear 88 fixed to

one end of the shaft 50 of the feed roller 37. At the end of each cycle of the paper feeding mechanism, the knife 41 is operated to sever the measured length of paper which becomes the blank from which the bottle cap is to be formed.

The shearing blade or knife 41 is carried between the upper ends of a pair of vertically reciprocable rods 110 (see Figs. 6 and 21) which are guided for sliding movement through bearings 111 fixed to the opposite inner walls of the bracket plates 32. The lower ends of the rods 110 are connected by a bar 112, to which is pivoted a connecting rod 113 which, as shown in Fig. 1, leads to a lever 114 pivoted on the shaft 12 and provided with a roller 115 engageable with a cam 116 (see Fig. 1a). This cam is also one of the set of cams 9, and is shaped to raise and lower the knife blade at properly timed intervals with respect to the feed of the paper. The knife blade cooperates with a shear block 117 (Fig. 3) over which the paper passes, the cutting edge of the knife being formed on an arch, as illustrated in Fig. 21, so that it will cooperate with the straight edge of the block 117 to produce the shearing action. The blade 41 is preferably formed of a steel plate which is slightly curved rather than flat, so that it may be brought into a proper position of adjustment with respect to the block 117 by means of screws 118 which pass through the blade and into a block 119 directly behind it, and also secured to the uppermost ends of the vertically reciprocating rods 110.

In order to prevent slipping of the paper during the shearing action of the knife, a presser foot 120 is carried by posts 121 which extend upwardly through the block 119. Springs 122 surround the posts 121 between the presser foot and the block and pins 123 limit the downward movement of the presser foot under influence of the springs 122. As the knife is moved downwardly to shear the paper, the presser foot cooperates with the shear block 117 to clamp the paper during the operation of the knife.

The paper blank is meanwhile received by the grippers 44 which comprise stationary jaw members secured to rack bars 90 and movable jaw members 91 pivoted to the stationary jaws by a pin 92 and urged to a gripping position by springs 93. The rack bars 90 are slidably mounted in opposed channel-shaped guides 94 (see Figs. 7 and 10) and are engaged by a pair of gears 95 fixed to a shaft 96 which is journaled in brackets 97 carried by two of the frame posts 2.

One end of the shaft 96 is fitted with a gear (not shown) which is enclosed by a housing 98. This housing also serves as a guide for a sliding rack 99, meshing with the said enclosed gear and connected by a rod 100 with a bell crank 101 mounted on the shaft 12 and having a roller 102 at its opposite end engageable with a cam 103 in the set of cams 9, against which it is retained by a spring 104. The said cam is shaped to impart reciprocation to the rack 99 and thus oscillate the gears 95 which, in turn, impart reciprocating movement to the racks 90 carrying the grippers 44.

As shown in Fig. 3, the pivoted jaws of the grippers 44 are provided with tails 105 which engage stops 106 secured to the channels 94 to swing the jaws to an open position as they approach the paper blank to be received by the grippers. The leading edge of the paper blank is received between the open jaws of the grippers and as the grippers are withdrawn by their racks 90 and 75

the associated operating mechanism, the tails 105 leave the stops 106 and the jaws close, gripping and carrying the paper blank to a properly centered position above the bottle on the elevator.

5 The tension of the springs 93, which close the jaws of the grippers, is sufficient to carry the paper but is not too great to permit easy removal of the paper from the grippers without the necessity of opening the jaws. The exact manner 10 in which the paper is withdrawn from the grippers through the action of the cap-forming mechanism will appear during the description of said mechanism.

It should also be noted here that the grippers 15 close upon the paper and have a slight movement away from the knife just prior to the shearing action of the knife. Due to this slight initial movement of the grippers, they are always in exactly the same position relative to the cut edge 20 of the paper and the centering of the printed legend over the top of the bottle is therefore not varied by the possibility of the grippers engaging the paper blanks at slightly different positions.

In order that the paper blank which has been 25 positioned over the top of the bottle on the elevator may be formed into a bottle cap, the elevator raises the bottle to a point with its top in the plane of the paper and, at the same time, a resilient plunger 125 (best illustrated in Fig. 3) 30 descends to the same plane so that the paper is clamped between the plunger and the bottle top. The elevator then continues its upward movement and the plunger recedes to carry the paper out of the grippers 44 by means of which it has been 35 brought into position over the bottle. The face of the plunger 125 is preferably of compressible material, such as rubber, backed with a shell 126 which is slidable on a rod 127.

The head 128 of a cap-forming tube 129 is fixed 40 to the rod 127 and the tube serves as a guide for the plunger 125 which may recede into the tube but which is normally urged downwardly under influence of a spring 130. A nut 131 on the lower end of the rod 127 limits the downward movement 45 of the plunger. The cap-forming tube 129 telescopes within a stripper cylinder 132 and the unit, which includes the cap-forming tube, resilient plunger and the rod 127 upon which they are mounted, is reciprocated through a link 133 connecting the upper end of the rod 127 with a crank 134 fixed to a shaft 135. The shaft 135 is 50 journaled in a pair of brackets 136, carried by two of the frame posts 2, and this shaft (as shown in Fig. 2) also carries a crank 137, connected by an adjustable rod 138 with a bell crank 139 on the shaft 13, this bell crank having a roller 140 held in engagement with the periphery of a cam 141 by a spring 142. This cam is so 55 timed that as the top of the bottle and the plunger 125 meet in the plane of the paper, the cap forming tube 129 begins to recede upwardly, the upward movement being slightly retarded with respect to the upward movement of the bottle carried by the elevator. The slight advance 60 movement of the elevator causes the top of the bottle to press the resilient plunger upwardly within the cap-forming tube, and consequently the paper, which is held between the plunger and the bottle top, is engaged by the wall of the tube and folded downwardly to form a marginal skirt around the neck of the bottle.

Prior to this upward movement of the bottle, a piece of string has been formed into a double half-hitch or clove-hitch in a position surround-

ing the path of movement of the bottle, so that as the bottle moves upwardly and the cap-forming tube moves downwardly, they pass within the loop formed by the string. The pre-formed clove-hitch of the string is then released so that a portion of it surrounds the skirted portion of the bottle cap and a portion of it surrounds the cap-forming tube 129.

At this time the stripper cylinder 132, which telescopes over the tube 129, descends to push that portion of the knot surrounding the cap-forming tube downwardly and off of the end of the tube, so that upon pulling of the opposite ends of the string, the knot is tightened about the skirted portion of the cap to secure the same with relation to the bottle. In Fig. 7 the bottle is shown after the cap has been formed and after the stripper cylinder has descended and the string has been tightened in this manner.

The stripper tube is guided through an opening in the intermediate table 4 and the mechanism for causing its descent to perform the stripping operation at the proper time is illustrated in Figs. 2 and 3. In these figures, the head of the stripper cylinder 132 is shown at 145. This head is connected by a link 146 with a crank 147 on a shaft 148 which is carried in brackets 149 depending from the lower surface of the upper table 5. The shaft 148 (see Fig. 1) also carries a crank 150 which is connected by a rod 151 with a bell crank 152 on the shaft 13, a roller 153 on said bell crank being held in engagement with a cam 154 by means of a spring which is not shown but which extends between the upper end of the bell crank 152 and the base 1 just behind the cam 154.

The string from which the tie which secures the cap to the bottle is formed is carried on a spool 160 (Fig. 1) rotatably carried on a bracket 161. The free end of the string is led from the spool over a split pulley or brake 162 which is operated during the tying of the knot in a manner which will presently appear. From the brake 162 the string passes over one of a pair of sheaves 163 carried on the outer end of a pivotally supported slack-take-up arm 164, then over one of a pair of sheaves 165, back over the other sheave 163, from which it passes under the other of the sheaves 165, which brings it to the level of a shuttle 166.

As illustrated in Figs. 3 and 9, the string passes through a guide loop 167 on the shuttle and then out to the end of the shuttle where it is threaded through a hole 168. The slack-take-up arm 164, which is also illustrated in Fig. 8, is pivotally and resiliently supported to prevent breakage of the string in the event of any sudden pull thereon, and is swung downwardly during the forming of each tie to provide a supply of slack string as it is required during the formation of the tie by the shuttle. The arm is pivoted upon a shaft 169, supported in brackets 170 and resiliently secured relative to the shaft through a fixed collar and a helical torsion spring 172. The torsion spring permits a slight downward swinging of the arm 164 and the shaft 169 is rocked periodically to swing the arm downwardly at desired intervals. The movement of the shaft and the timing thereof are effected through the crank 173, secured to one end of the shaft and, as illustrated in Fig. 2, connected by a rod 174 with a bell crank 175 on the shaft 12, the bell crank 175 carrying a roller 176 which is maintained in engagement with a cam 177 by a spring 178.

The shuttle, in order to guide the string into

the shape of a loosely formed clove-hitch later to be tightened about the skirt of the cap to secure the same to the bottle, passes through a circular path on one plane, then drops to a lower plane and repeats its circular movement. The mechanism for effecting this movement of the shuttle will be described before reference is made to the structure which supports the loosely formed tie in a position which makes it possible for the bottle to be moved into the same preparatory to its being tightened.

Referring to Figs. 3, 6 and 8, the shuttle 166 is shown as pivotally supported at the outer ends of a pair of identical cranks 180. These cranks 180 are secured to the lower ends of a pair of vertical shafts 181 which pass upwardly through and are journaled for rotation in the intermediate table 4 and the upper table 5. Gears 182 are secured one to each of the shafts 181 and mesh with a gear 183 on a short shaft 184 extending through the upper table 5. The gear 183 is sufficiently long to permit limited vertical movement of the shafts 181 without moving the gears 182 out of mesh. The short shaft 184 is provided with a pivotal gear 185, at its upper end, which meshes with a pivotal gear 186 on a horizontal shaft 187 journaled in bearing brackets 188 fixed to the top of the upper table 5. The shaft 187 is rotated through 360° alternately in opposite directions, and imparts rotation of the gear 183 through 360° intermittently in one direction only.

The structure for producing this effect is illustrated in Figs. 4 and 5, where the gear 183 is illustrated as loosely mounted on the short shaft 184 but connected to the shaft through a spring-pressed pin 189 which rides over the surface of a cam 190, fixed to the shaft, upon rotation one direction, and engages with a shoulder 191 on said cam to impart rotation to the gear 183 upon rotation of the shaft in the opposite direction. On its upper surface the gear 183 carries a cam 192 (also illustrated in Fig. 8) provided with a notch for registry with a spring-pressed pawl 193 to insure stopping of the gear and shuttle operated by it in a properly centered position at the termination of each cycle of operation.

Driving and timing of the horizontal shaft 187, which rotates alternately in opposite directions to effect the movement of the shuttle through the mechanism just described, are effected through a gear secured to the outer end of this shaft and enclosed in a housing 195 (see Fig. 1), which housing also serves to guide a rack bar 196 in mesh with said gear. The rack bar is connected by a rod 197 with a bell crank 198 carrying a roller 199 in engagement with a cam 200. The cam 200 is provided with a double depression so that upon each complete rotation of the main drive shaft 7, two complete circular movements are effected. A spring 200a adjacent to the upper end of the rod 197 maintains the roller against the cam.

The mechanism for effecting movement of the shuttle from one plane to another between its successive circular movements and then returning it to the first plane after completion of its knot-forming operation, is shown in Fig. 3. This mechanism comprises a yoke 201, which has arms embracing both of the vertical shafts 181 and engaging with the lower surfaces of the gears 182 and the upper surfaces of a pair of collars 202 secured one to each of the shafts 181. A link 203 connects the yoke 201 with a crank 204 on a shaft 205 which is journaled in gearing brackets 206 on the intermediate table 4. The outer end

of the shaft (as shown in Figs. 2 and 6) carries a crank 207 connected by a rod 208 with a bell crank 209, which carries a roller 210 bearing against a cam 211 and restrained to follow the cam under influence of a spring 212.

The shuttle forms the tie about two sets of pins, and these pins may be retracted through plates which cause the tie to be stripped from them so that upon tightening it will be drawn into position around the neck of the bottle. The upper set of pins, which are four in number, are shown in Figs. 3, 7 and 17, at 215. These pins extend upwardly from a pin shelf 216, disposed beneath a pin stripper plate 217. The lower set of three pins, illustrated at 218, extend upwardly from a pin plate 219 and through a pin stripper plate 220. The lower set of pins are longer than the upper set, as it is necessary that they pass through portions of the string gripper actuating mechanism (hereinafter to be described).

Both the upper pin shelf 216 and the lower pin shelf 219 are carried by a set of four vertically extending posts 221 which are slidably received through holes formed for this purpose in the intermediate table 4. The posts are joined at their upper ends by a top plate 222, and springs 223 (shown in Fig. 7) extend between the top plate 222 and the table 4 normally to urge the posts 221 and the pin-supporting plates downwardly. A collar 224 surrounding the stripper cylinder 132, which passes through the top plate 222, engages the bottom surface of the top plate and normally retains the pins in their uppermost position. Spacers 225 surrounding the posts 221 above the table 4 limit the downward movement of the posts and the pins. The pin-stripper plate 217 is supported in a fixed position by three posts 226, which extend downwardly from the intermediate table 4, and pin-stripper plate 220 is secured to the top of a ring 227 which is, in turn, secured to a plate 228 supported on downwardly extending posts 229 at one edge and fixed relative to two of the frame posts 2 at its other edge.

With the pins in their uppermost position, the free end of the string is held by a gripper which is disposed at the level of the bottom set of pins and which is presently to be described in detail, as illustrated in Fig. 11. The shuttle then moves upwardly and circles the top pins 215 to lay the string about these pins so that it will assume the position illustrated in Fig. 12. Having completed this circular movement, the shuttle again drops to its starting plane and circles the bottom pins 218 to lead the string about these pins in the manner illustrated in Fig. 13. The string having thus been led about both sets of pins, is in the form of a loosely tied clove-hitch, as is illustrated in Fig. 16, which shows the position of the shuttle just prior to the final portion of its movement which brings it to a position of rest.

With the knot thus formed about the pins, the bottle is moved upwardly, it being understood that at this time the paper blank has been clamped to the top of the bottle by the resilient plunger 125 which has receded into the cap-forming tube 129 which folds the margin of the blank downwardly about the neck of the bottle. The stripper tube 132 then starts its downward movement, the initial part of this movement permitting the posts 221 to move downwardly under tension of the springs 223 so that both the upper and lower sets of pins, around which the tie is formed, are caused to recede through the pin stripper plates 217 and 220. As the tie is released its upper portion surrounds the cap-forming tube above the

bottle and its lower portion is disposed around the neck of the bottle. Further downward movement of the stripper tube 132 engages and slides that portion of the tie which surrounds the cap-forming tube downwardly until it comes into place around the neck of the bottle and the tie is then drawn tightly about the bottle by the combined action of the string grippers, the slack-take-up arm 164 and the string brake 162.

10 The end of the string is held by one of a pair of grippers during the time that the shuttle is leading the string around the pins which support it in the form of a tie. The other one of this pair of grippers is meanwhile moving into a position to grip the string at the other end of the tie to lead it into a cut-off knife and carry it to the position originally occupied by the first gripper and to hold it during the next tie-forming cycle of the shuttle. The two grippers follow each other in a circular path and exchange functions for alternate tying operations. The grippers, which are generally indicated at 230 and 231 in Fig. 11, may, for the present, be considered as identical. Each gripper comprises a base plate 232 which carries an outwardly extending string brake operating ear 233 and a stationary gripper jaw 234. A movable gripper jaw 235 is pivoted relative to each of the base plates by a pin 236, and the plates which carry these movable jaws are provided with outwardly extending tails 237.

30 Springs 238 extending between these tails and the base plates normally maintain the jaws in a gripping position. For the sake of simplifying the description of the gripper operation, the complete circular path of one gripper will be described in the terms of the various stations at which the gripper stops during its circular travel and the functions that it performs as it moves from station to station. It is to be understood, however, that the two grippers are following each other and performing their individual functions simultaneously during each cyclic operation of the machine.

40 45 In Fig. 11, the gripper 230 is shown in its initial position, or resting at that point in the cycle of its operation which will hereinafter be referred to as station A; in Fig. 15, the same gripper is at station B; in Fig. 11, the gripper 231 is at station C; and in Fig. 13, the gripper 231 is at station D. While the four stations A, B, C and D represent the major positions of the grippers, it being understood that each gripper stops at each station during its movement through 360°, there is a temporary stop or hesitation of the grippers as they attain position E, illustrated in Fig. 15.

50 55 The end of the string is held by the gripper in position A while the shuttle leads the string around the pins which support the loosely formed tie. After the tie has been formed, the bottle moved into position to receive the tie, and the tie-supporting pins withdrawn, this gripper moves to station B for the purpose of taking up slack in the free end of the string and pulling the tie tightly about the neck of the bottle. Upon the initial portion of the gripper movement from station B to station C, the tail 237 strikes a stationary cam 240 to swing the movable jaw 235 about its pivot 236 and release the string just prior to the withdrawal of the bottle upon which the capping and tying operations have been completed. The gripper then completes its movement to station C. Upon moving from station C to station D, the tail 237 of the movable gripper jaw engages a stationary cam 241, placing the gripper

in a wide-open position for reception of the string at the point where it leaves the pre-formed tie and at the time that the bottle is being brought into position within the tie.

As the gripper approaches station D, the ear 233 engages the edge 242 of a string brake lever 243. This lever 243 is pivotally carried by one of the posts 239 and is connected by a rod 244 (see also Figs. 1 and 2), which rod extends through brackets 245 and serves as an axle for the split sheave 162 which acts as a string brake. Springs 246 are disposed about the rod at opposite sides of sheave 162, and nuts 247 on the end of the rod retain the assembly in place. When the lever 243 is pivoted, due to its engagement by the ear 233 on the gripper member, the rod 244 is drawn inwardly to compress the split sheave 162 and clamp the string therein temporarily to prevent further unwinding of the string 260. The springs 246 serve to cushion the clamping action and prevent cutting or bruising of the string as this action takes place.

At the time that the brake is applied to the string in the manner just described, the slack-take-up arm 164 assumes a lowered position and immediately after the brake has been applied, this arm is raised to take up any existing slack in the portion of the string that is led over the sheaves 163 and 165 and to tighten the string around the bottle neck prior to cutting of the string so that a firm knot will be produced to effect securing of the cap about the neck of the bottle. As the gripper leaves station D, the string, now having been tightened around the neck of the bottle, is received between the open gripper jaws. As the movement of the gripper progresses, the tail 231 rides off of the cam 241 to close the jaws upon the string and the ear 233 releases the brake lever 243. The gripper then hesitates in position E, as illustrated in Fig. 15, in which position it has carried the string into a knife 250.

The knife 250 (see Figs. 1, 6 and 7) consists of a blade having a V-shaped slot in one of its vertical edges and carried for vertical reciprocal movement in a guide block 251 secured adjacent to the lower edge of the stripper cylinder 132. A pair of adjusting screws 252, in the block 251, press a spring plate 253 against the blade, causing frictional resistance to its vertical reciprocation. As the stripper cylinder descends, the string is led into the V-slot of the knife and the bottom end of the blade engages the plate 220, causing the blade to recede into the block and shear the string. When the stripper cylinder returns to its uppermost position, the top end of the blade 250 engages the intermediate table 4 and causes the blade to slide through the block and assume its lowermost position relative to the block.

The string having thus been severed, the gripper moves on from position E to its position of rest at station A, to which position it carries the string and retains it preparatory to the next tie-forming cycle of the shuttle.

The gripper movements from stations A to B and B to C are timed differently than the gripper movements from stations C to D and back to A, and as the two grippers are operating simultaneously in a different manner, yet performing the same functions alternately, it is desirable to employ two separate gripper driving mechanisms. One of these driving mechanisms actuates both of the grippers successively during their movements from A to B and B to C, and the other driving mechanism actuates the grippers suc-

sively as they move from C to D and back to A.

The manner in which the driving mechanisms effect movement of the gripper 230 through a 360° cycle will first be described, and this description will be followed by the description of the movement of the gripper 231 through its 360° cycle. The gripper 230 is secured by screws 255 to the raised hub of the ring gear 256 (see also Fig. 3) which rotates about the ring 227. A pinion 257 (see Fig. 2) meshes with the toothed periphery of the ring gear 256 and is carried by the upper end of a shaft 258. The lower end of the shaft 258 carries a pinion 259, which meshes with a gear 260 freely rotatable about the vertical shaft 261 (as best illustrated in Figs. 17 to 20, inclusive). The upper surface of the gear 260 carries spaced pins 262 and 263 for engagement by the lower pawls in two sets of pawls 264 and 265. The pawls 264 and 265 are referred to as "sets" by reason of the fact that the two pawls in each set are fixed to their respective pivot pins 266 and 267 so that the pawls of each set must swing together.

The pivot pins are rotatably journaled at the outer ends of separate levers 268 and 269, both of which are mounted for pivotal movement about the vertical shaft 261. The pawls 264 and 265 are urged inwardly by springs 264a and 265a, respectively. The lever 268 is caused to oscillate, being connected by a rod 270 (see Figs. 2 and 20) with a bell crank 271, which carries a roller 272 pressed into engagement with the surface of a cam 273 by a spring 274. The crank 269 is similarly oscillated, being connected by a rod 275 (see Fig. 1) with a bell crank 276 which has a roller 277 engaging a cam 278 under influence of a spring 279.

Upon the first oscillatory movement of the lever 268 the lower pawl 264 engages the pin 262 to rotate the gear 260, and, through the pinion 259, shaft 258 and pinion 257, impart rotation to the ring gear 256, and move the gripper 230 from station A to station B. As the rotary movement thus imparted to the gear 260 is substantially 90°, the pin 263 thereon is brought by this movement into position for engagement by the lower pawl 264 upon its next subsequent oscillation, whereupon the gripper will be moved from station B to station C. This movement of the gear 260 brings the pin 262 into position for engagement by the lowermost of the pawls 265. Oscillation of these pawls will, therefore, act successively upon the pins 262 and 263 to move the gripper from station C to station D, and from station D back to station A. As one cam has been effective to move the gripper throughout approximately one-half of its 360° cycle and the other cam effective to move it throughout the remaining half of its cycle, it is apparent that these cams may be differently contoured to effect any desired speed and timing of the operation of the gripper as it is moved from any one station to the next.

The other gripper 231 is secured by screws 285 to the surface of a ring gear 286 which (as shown in Fig. 3) rides on top of the ring gear 256 and is centralized about the raised central portion of the same. This ring gear 286 meshes with a pinion 287 at the upper end of a shaft 288. Adjacent its lower end the shaft 288 carries a pinion 289 in mesh with a gear 290 (see Figs. 18 to 20), and the gear 290 carries a pair of pins 292 and 293 extending downwardly from its bottom face which are engageable by the uppermost

pawls in the sets 264 and 265. The radial positions of the pins 292 and 293, with respect to the pins 262 and 263, are such that their engagement and movement by the oscillating pawls in the sets 264 and 265 will compel the grippers to follow each other about their circular path in the proper timed relation.

Assuming the machine to be in continuous operation, it is most convenient to consider it as commencing a cycle during the time when the elevator is being lowered to remove a bottle upon which the capping and tying operations have been completed. It is at this time that the shuttle is operating to guide the string into the shape of a loosely formed clove-hitch supported by the pins which are later to be withdrawn to permit the hitch being tightened about the skirt of the cap where it surrounds the bottle neck.

As the loosely formed hitch or knot is being completed, an uncapped bottle is placed upon the elevator, from which the last bottle has been removed, and the paper feed mechanism operates to advance the paper the length of one blank. The blank is sheared from the roll and carried by the grippers 44 to its position over the bottle on the elevator. The bottle rises and the plunger 125 descends to meet in the plane of the paper, thus clamping the paper and then drawing it upwardly. Owing to the greater upward speed of the bottle and the resilient mounting of the plunger head, the cap-forming tube 129 has a movement which is downward relative to the bottle and the lower edge of this tube engages and folds the margin of the cap blank down to form the desired skirt which surrounds the neck of the bottle and around which the string passes to secure the cap to the bottle.

The bottle having been raised to a position where its neck is encircled by the loosely formed tie, the pins which support the tie are withdrawn. The gripper which is holding the leading end of the string and the slack-take-up arm 164 which engages the string before it passes through the shuttle are then actuated to place a tension on the ends of the knot and draw it tightly about the skirt of the cap. During the tightening operation, the stripper cylinder 132 descends to push downwardly any portion of the knot which may have remained on the lower end of the cap-forming tube so that the entire knot will come into its intended position around the bottle neck. This downward movement of the stripper cylinder actuates the string knife to sever one end of the string where it leaves the tie, and the other end of the string is released upon the movement of the gripper which causes it to open. This permits the bottle to move downwardly with the elevator during the first steps of the next succeeding cycle of operation.

The string employed may be of any suitable type having the required strength, and it is to be noted that the knot which has two projecting ends is formed without the necessity of employing any mechanism for tucking either of these ends under the portions that have already been passed around the object to be tied. The knot is secure against accidental removal, yet may be untied by simply pulling upwardly on either of its projecting ends.

The paper of which the cap is formed is preferably of a type that has been treated to render it highly impervious to moisture. It is relatively thin and comparatively inexpensive. Owing to the fact that inexpensive paper and plain string may be used, the cost of capping bottles

with the machine is far below that of capping containers under presently known methods which require pre-formed pasteboard caps and fastening means of metal or specially treated twines.

Although the invention has been described and illustrated in a specific form, it is to be understood as limited only by the appended claims.

Having described my invention, what I claim

10 and desire to secure by Letters Patent is—

1. In a machine of the character described, mechanism for tying and supporting a knot in a position to receive an object to be tied comprising a first set of pins disposed in one plane, a

15 second set of pins disposed in a lower plane, a shuttle member for leading a string to a position surrounding and supported by said pins, and means for moving the shuttle around the pins of the first set, then down, and then around the 20 pins of the second set whereby the string will assume the form of a loosely tied clove-hitch.

2. In a machine of the character described, mechanism for tying and supporting a knot in a position to receive an object to be tied comprising a first set of pins disposed in one plane,

25 a second set of pins disposed in a lower plane, a shuttle member for leading a string to a position surrounding and supported by said pins, means for moving the shuttle around the pins

30 of the first set, then down, and then around the pins of the second set whereby the string will assume the form of a loosely tied clove-hitch, means for moving an object to be tied into the knot, means for retracting all of the pins to release the knot, and means for putting a tension on the string at opposite ends of the knot to draw it tight about the object.

3. In a machine of the character described, a set of retractable pins, means for leading a string

40 about said pins to form a loosely tied knot, a gripper for holding the free end of said string stationary as it is being led about the pins, a string cutter, and a second gripper movable to engage the string after the knot is formed and

45 lead it into the cutter.

4. In a machine of the character described, a set of retractable pins, means for leading a string about said pins to form a loosely tied knot, a gripper for holding the free end of said string

50 stationary as it is being led about the pins, a string cutter, a second gripper movable to engage the string after the knot is formed and lead it into the cutter, and means for moving said

55 grippers intermittently in a circular path whereby the second gripper will carry the cut end of the string to the position of the first named gripper and the two grippers will perform the same functions alternately.

5. In a machine of the character described,

60 means to tie and support a knot in a position to receive a capped container to be tied, an elevator for supporting a container, means to place a paper blank over the container on the elevator, means to raise the elevator, a cap-forming tube,

65 means to lower said tube to meet the container and form a skirted cap thereon within the area surrounded by the knot, means to release the knot, and means to draw the knot tight about the skirt of the cap.

6. In a machine of the character described, means to tie and support a knot in a position to receive a capped container to be tied, an elevator for supporting a container, means to place a paper blank over the container on the elevator,

75 means to raise the elevator, a cap-forming tube,

means to lower said tube to meet the container and form a skirted cap thereon within the area surrounded by the knot, means to release the knot, a stripper cylinder telescoping over the cap-forming tube and movable downwardly to remove any portion of the knot which surrounds the tube, and means to draw the knot tight about the skirt of the cap.

7. In a machine of the character described, a support for a supply of string, a gripper for holding the free end of the string, a shuttle having an eye through which the string passes intermediate the gripper and the supply, means for moving the shuttle to lead the string into the form of a knot, a resiliently tensioned slack-take-up arm engaging the string between the supply and the gripper, means for moving the slack-take-up arm to provide slack for the formation of the knot by the shuttle, a string brake between the slack-take-up arm and the supply, and means effective after completion of the knot to apply the brake, move the arm and move the gripper to effect tightening of the knot.

8. In a method of constricting an element having flexible walls, those steps which comprise forming a loop of flexible strand, transferring said loop to a transfer member, bringing said ele-

ment into position for receiving the loop, transferring the loop to and about the flexible walls of said element, and constricting and securing in constricted condition the loop about said walls.

5 9. In a method of constricting elements having flexible walls, those steps which comprise forming a loop of flexible strand, transferring said loop to a transfer member, bringing one of said elements into position for receiving the loop, 10 transferring the loop to and about the flexible walls of said one element, constricting the loop on said walls, and forming another loop for transfer on another element while said one element is being replaced by said other element in 15 the position for receiving its loop.

10 10. A bottle capping machine comprising mechanism for forming a clove hitch from a continuous length of twine, a device for inserting a capped bottle into said mechanism and for removing the bottle after the cap has been secured thereto, means for exerting a pull on the ends of the clove hitch so as to constrict it and thus secure the cap on the bottle, and means for causing said mechanism to form another clove hitch while the capped bottle is being replaced by another bottle.

GUNNAR ARNBERG.
